Primary Examiner — Andrew Kerr

(57) **CLAIM**

The ornamental design for a lunch bag, as shown and described.

DESCRIPTION

FIG. 1 is a perspective view of a lunch bag showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in FIGS. 1-5 depict stitching which forms part of the claimed design. The broken lines in FIG. 7 depict portions of the claimed design that form no part of the claimed design.

1 Claim, 7 Drawing Sheets(56)
